(57) **CLAIM**

The ornamental design for a pump for liquids, as shown and described.

DESCRIPTION

The patent or application file contains at least one drawing executed in color. Copies of this patent or patent application publication with color drawing(s) will be provided by the Office upon request and payment of the necessary fee.

1. Pump for liquids

1.1 : Front

1.2 : Top

1.3 : Left

1.4 : Right

1.5 : Bottom

1.6 : Perspective

The claimed design is for the liquid pump which is a cylindrical, orange-colored object and is narrowed in the middle and surrounded by a spiral of metal in the middle; at the upper end, a notch shows, from the middle of which a hexagonal thread protrudes; the underside shows no notch but a closed surface from which metal rollers bulge out at two opposite points; fig. 1.1 is a front view of the liquid pump; fig. 1.2 is a top view of the liquid pump; fig. 1.3 is a left side view of the pump lying lengthwise on the surface so that the metal rollers on the underside can be seen from the side; fig. 1.4 is a right side view of the pump lying lengthwise on the surface so that the metal rollers on the underside can be seen from the front and as recessed half rings; fig. 1.5 is a bottom view of the underside of the pump; fig. 1.6 is an oblique perspective view showing the underside of the pump in the front of the picture.
